UNITED STATES PATENT OFFICE.

AUGUSTE DUTREUX, OF ISSY LES MOULINEAUX, FRANCE, ASSIGNOR TO SOCIÉTÉ ANONYME POUR L'ECLAIRAGE ELECTRIQUE DES VÉHICULES, OF ISSY LES MOULINEAUX, FRANCE, A CORPORATION OF FRANCE.

INTERRUPTER AND SPARK-ADVANCER FOR INTERNAL-COMBUSTION ENGINES.

1,280,102.

Specification of Letters Patent. Patented Sept. 24, 1918.

Application filed December 6, 1916. Serial No. 135,511.

To all whom it may concern:

Be it known that I, AUGUSTE DUTREUX, engineer, of 26 Rue Jean Jacques Rousseau, at Issy les Moulineaux, Department of the Seine, France, citizen of the French Republic, have invented certain new and useful Improvements in Interrupters and Spark-Advancers for Internal-Combustion Engines; and I do hereby declare the following to be a full, clear, and exact description of the invention, such as will enable others skilled in the art to which it appertains to make and use the same.

The present invention relates to interrupters and spark advancers for internal combustion engines, and has for its object to provide an arrangement which with the aid of a coupling acting by centrifugal force will permit the spark to be advanced automatically with reference to the position of the piston, in accordance with variations in speed of the motor, and at the same time notwithstanding changes in speed of the motor automatically maintain constant the duration of the engagement of the contacts of the interrupter.

The invention is applicable to all kinds of generators of electricity (battery, magneto, dynamo, dynamo-magneto and the like) for ignition purposes or for ignition combined with the lighting of vehicles or for starting internal combustion motors.

Heretofore the coupling acting by centrifugal force has been interposed between the armature shaft of the ignition machine and the operating shaft of the latter. This arrangement has given good results for ignition generators, such as magnetos which, for a given speed, always provide at this speed a constant quantity of energy.

It is, however, quite otherwise when the ignition generator is, for example, a dynamo which also furnishes the lighting of the vehicle.

Whether the generator furnishes light or not the energy to be transmitted to the armature will be variable for a given speed and this will be still more true in the case of a generator of considerable size. It follows that a centrifugal coupling furnishes for a given speed different degrees of ad-

vance of the spark according to whether the dynamo is fully or lightly loaded with resulting defective operation of the internal combustion engine.

It has been proposed to obviate this disadvantage by placing the centrifugal coupling between the armature of the ignition generator and the interrupter coupled directly to the distributor. The latter while being an improvement on the former arrangement has the disadvantage of requiring (1) an armature, (2) an armature shaft which must be directly actuated by the motor shaft because the disposition of the armature with respect to that part of the armature which carries the interrupter and transmits movement to the distributor must conform absolutely to a given value for a predetermined speed.

The present invention has for its object to provide an arrangement in which the position and speed of the armature with respect to the automatic advance device may be anything desired and which will permit of the armature being rotated by any suitable form of drive, such as a rigid drive through an elastic coupling, or by belt gearing, cone, friction or the like. Further, whether the armature is coupled up or not the automatic advance is always in action as it depends solely on the speed of the petrol motor.

It is also to be noted that if the source of current for ignition purposes is a battery of accumulators or of cells, the operation of the present arrangement always remains the same.

The accompanying drawings show by way of example a constructional form of the invention.

Figure 1 is a view partly in section of one form of an arrangement in accordance with the invention.

Fig. 2 is a perspective view on an enlarged scale of one of the parts of Fig. 1.

Figs. 3, 4, 5, 6 and 7 show, by way of example, various forms of rigid or elastic couplings which may be employed as driving agents between the generator and the ignition device.

Fig. 8 is a view partly in vertical section of a modification.

Fig. 9 is a front view of the same.

Fig. 10 is a vertical sectional view of a modification having two cams, the relative displacement of which governing the duration of engagement of the contact of the interrupter.

Fig. 11 is a front view of the arrangement showing the cams.

Figs. 12 and 13 illustrate respectively two views of the arrangement on the line A B of Fig. 1 at rest and in full operation.

Figs. 14 and 15 show the corresponding positions of the cams.

Referring now to Fig. 1, the shaft of the dynamo is shown at 1 and a shaft of a combustion motor at 2.

In the constructional form of coupling between the two shafts shown in Fig. 1 no relative movement is produced between 20 the driving shaft and the armature shaft, but this is only a special case and Figs. 2, 3, 4 and 5 show that driving by toothed pinion, belt, cone or elastic coupling may be employed, variations in speed between the two 25 shafts, their respective positions and driving slip having no influence on the operation of the system.

The centrifugal governor 3 is mounted on the shaft 2 of the motor and consists of two 30 parts independent one of the other 4 and 5, of the shape indicated, one 5 of which is fast and the other 4 is loose on the shaft 2.

Under the influence of centrifugal force a suitable device shifts the loose part 4 with 35 respect to the part 5 fast on the shaft imparting a rotary movement to the part 4 around the shaft 2.

Said device may for example comprise oscillating weights or balls suitably arranged 40 on a plate 6 also loose on the shaft 2. These weights or balls may also conveniently directly connect the two parts 4 and 5 without other support.

On an increase of speed the balls or 45 weights displace the part 4 on which is immovably fixed a toothed wheel 7 which controls by means of a toothed wheel 8 the brush 9 of the distributor. A sleeve 10 keyed on an extension in the form of a socket of the 50 part 4 is capable of sliding on a key 11 of the latter parallel with the axis of the shaft 2, the sleeve 10 being guided during its displacement by a groove 12 cut around the shaft 2 and of appropriate shape and by a 55 screw 13.

The exterior surface of the sleeve 10 forms a cam and comprises one or more bosses 14, 14¹ and 14² the boundaries of which are appropriately inclined. An oscillating lever 15 60 is in constant engagement at its extremity with the outer surface of the sleeve 10 and carries at its other extremity a contact 16 which makes contact with a fixed contact 17 when a boss of the cam engages with the 65 extremity of the arm 15.

The interrupter thus formed acts to break periodically a circuit including a source of current such as a dynamo, battery cells.

From the foregoing it will be seen that with a predetermined speed and independently of the power transmitted to the armature of the generator, there will be a predetermined movement between the parts 4 and 5, and consequently a well defined position of the sleeve 10 depending upon the form of the groove 12; the length of the boss or bosses of the cam with respect to the arm 15 of the interrupter will determine the position of the break or breaks per revolution of the explosion motor. The brush of the distributor will be advanced or retarded by a corresponding amount.

Under these conditions with cams of suitable shape the duration of engagement of the contacts of the interrupter may easily be 85 maintained sufficiently constant in spite of variations in speed of the motor at the same time that the cam actuating the interrupter as well as the distributing mechanism is displaced with respect to the shaft 2.

In the constructional form shown in Figs. 8 and 9 the part 5 of the centrifugal governor is provided with two fingers 20 and 21 which slide in the part 4 by means of the slots 22 and 23. The part 4 carries two or 95 more pawls 24 and 25 capable of oscillating around pivots 26 and 27. Springs 28 and 29 secured to the part 4 maintain the pawls 24 and 25 in engagement with the fingers 20 and 21 against the action of centrifugal 100 force. The exterior edges of the pawls 24 and 25 are formed as cams and are adapted to engage with the extremity of the arm 15 of the interrupter.

The operation is as follows:

At slow speed the pawls 24 and 25 act on the interrupter 15 with a small part of their length only, when the speed increases the fingers 20 and 21 slide in the slots 22 and 23 by reason of the displacement of the part 4 110 with respect to the part 5 of the regulator.

The pawls 24 and 25 are raised by the fingers 20 and 21 and act in accordance with the shape which has been given to their internal and external portions by the aid of 115 the arm 15 on the closure of the contacts 16 and 17 in such a manner that the time of closure of these contacts will be constant and independent of the speed of rotation.

It should be understood that the pawls 24 and 25 may, instead of closing the interrupter, open the latter and that the rods 20 and 21, instead of being fixed on the part 5, may be fixed on the shaft 2 which is fixed with respect to this part.

Figs. 10 and 11 show a modification in which instead of employing a cam having an oblique edge sliding and turning on the driving shaft, two cams are employed provided with abutments, the relative displacement of 130

which governs the duration of engagement of the contacts of the interrupter. The member 4 displaced relatively to the member 5 through an angle dependent upon the speed of the shaft 1 is provided with four projections 30 acting as cams for actuating contacts 16 and 17 of the interrupter of the low tension winding of the magneto or of the primary of the ignition coil. One of these contacts is fixed, the other 16 being fast on a lever 31 which rotates about a pivot 32.

Closure of the contacts 16 and 17 is insured by the spring 33. At the extremity of the lever 31 a rubbing point 34 separates the contacts under the action of the cams. The part 4 is provided with two slots 35 in which a pin 36 slides. On this pin are pivoted the heads of two rods 37 and 38 (Figs. 10 and 13) the ends of which can rotate, that of the rod 38 around a pin 39 fixed in the part 3 and that of the rod 37 around a pin 40 mounted in a plate 41 loose on a part of the piece 4 concentric with the shaft 1. Movement is communicated to the plate 41 from the part 4 by the pins 36 and 40 and the rods 12. The plate 41 carries projections 42 which act as cams placed at the side of the cams 30. The rubbing point 34 always rests on both cams, the right-hand edges of the cams 30 bringing about the rupture of the circuit while the left-hand edges of the cams 42 control its closure when the direction of rotation is that indicated in Fig. 11.

The operation of the arrangement is as follows:

At slow speed parts 5, 4 and 41 occupy the positions indicated in Figs. 10, 11 and 13. The cams 30 and 42 occupy the positions indicated in these figures, that is to say the closure of the contacts 16 and 17 takes place while the device rotates through an angle β comprised between the radii leading from the center of the ascending and descending parts of the right and left edges of the bosses 30 and 42 and the closure during the rotation through an angle α included between the last mentioned radius and the adjoining radius of the part 30. When the speed increases the part 4 is displaced with respect to the part 3 by the interposed regulator and acts on the part 41 through the rods 37 and 38 so as to displace angularly the part 41 relatively to the part 4. The cams 30 and 42 are thus both displaced angularly but by unequal amounts the angular displacement of one being double that of the other. The angle α regulating the engagement of the contacts 17 and 16 can be given suitable dimensions to the rods, obtain a duration of contact independent of the speed of the motor at the same time that an automatic regulation of the advance of the ignition is secured.

It is to be understood that the constructional details may be modified without departing from the spirit of the invention.

I claim:

1. In an arrangement for automatically advancing the ignition of internal combustion motors, the ignition system including a distributer, an interrupter; a centrifugal governor interposed between the shaft of the motor, the distributer and the interrupter, a cam piece adapted to be moved by the governor to displace the interrupter and the brush of the distributer in accordance with the speed of the motor shaft and independently of the energy transmitted to the dynamo.

2. In an arrangement for automatically advancing the ignition of internal combustion motors, the ignition system including a distributer and an interrupter; a cam piece slidable on the motor shaft; and a centrifugal governor for moving the cam piece axially, the cams on said cam piece being arranged to engage the interrupter contacts in such manner as to obtain substantially constant engagement of the interrupter contacts irrespective of the speed of the driving motor.

3. In an arrangement for automatically advancing the ignition of internal combustion motors, the ignition system including a distributer and an interrupter; a cam piece slidable on the motor shaft; a centrifugal governor including two plates for moving the cam piece axially, the cams on said cam piece being arranged to engage the interrupter contacts in such manner as to obtain substantially constant engagement of the interrupter contacts irrespective of the speed of the driving motor, the cam piece being rotatable with one of the plates of the governor, but adapted to slide on the motor shaft in such manner that, for each position of the shaft and cam piece the latter will occupy a predetermined position with respect to the arm of the interrupter.

4. In an arrangement for automatically advancing the ignition of internal combustion motors, the ignition system including a distributer and an interrupter; a centrifugal governor interposed between the shaft of the motor, the distributer and the interrupter, said governor including a pair of plates, and-cam shaped pawls mounted on one of said plates, which pawls are adapted to be displaced by the displacement of the parts of the governor, the pawls being so shaped as to cause substantially constant engagement of the interrupter contacts irrespective of the speed of the driving motor.

5. In an arrangement for automatically advancing the ignition of internal combustion motors, the ignition system including an interrupter for the primary circuit, a pair of cams displaceable with relation to each

other and with relation to the motor shaft, the latter displacement being proportional to the speed of rotation of the shaft.

6. In an arrangement for automatically advancing the ignition of an internal combustion motor, a sleeve on the motor shaft, a plate associated with said sleeve and displaceable angularly with relation thereto, a cam, a centrifugal governor connecting the cam to the plate, the governor being arranged to displace the cam through an angle depending on the speed of the motor shaft, a second plate loose on the shaft, a cam mounted thereon and displaceable an-
- 10

gularly with relation to the first plate to a 15 degree equal to the displacement existing between the first plate and the sleeve, and means for causing such displacement of the second cam including a pair of rods fixed to the second plate and to the sleeve and 20 connected at their free ends by a pin moving in a slot in the second plate.

In testimony whereof I affix my signature, in presence of two witnesses.

AUGUSTE DUTREUX.

Witnesses:

HENRI COHEN,
CHAS. P. PRESSLY.
